United States Patent Office

Des. 215,667

Patented Oct. 21, 1969

215,667

DISPENSER FOR LIQUID SOAP OR THE LIKE

Myron N. Kane, River Forest, Ill., assignor to Madison Chemical Corporation, a corporation of Illinois

Filed Dec. 18, 1968, Ser. No. 15,036

Term of patent 14 years

Int. Cl. D6—01

U.S. Cl. D33—30

FIG. 2

FIG. 1

FIG. 1 is a front perspective view of a dispenser for liquid soap or the like showing my new design; and

FIG. 2 is a rear perspective view thereof.

I claim:

The ornamental design for a dispenser for liquid soap or the like, substantially as shown.
